INTERNAL-COMBUSTION ENGINE

Clifford S. Goby, Cleveland, Ohio, assignor of
one-half to Frank Kramer, Cleveland Heights,
Ohio

Original application November 13, 1939, Serial No.
303,942, now Patent No. 2,316,160, dated April
13, 1943. Divided and this application October
14, 1942, Serial No. 461,987

2 Claims. (Cl. 123—193)

This invention relates to internal combustion engines, and more particularly to engines of the type shown in my application Serial No. 303,942, filed November 13, 1939, now Patent No. 2,316,160, issued April 13, 1943, of which this application is a division.

The general purpose and object of the invention herein set forth is to provide an internal combustion engine of the type shown in the aforesaid application with efficient means for anchoring the cylinder heads and casings to the bases provided therefor; and, more limitedly, to provide anchoring means of this general character which is designed to cooperate with certain structural features of the cylinder casing, as will be pointed out hereinafter.

I realize the foregoing objects in and through the construction and arrangement of the parts shown in the drawings hereof, wherein Fig. 1 represents an elevational view, with parts broken away, of a portion of a radial engine such as is adaptable for use with aircraft and showing the bases to which the cylinders (including the heads) are secured; Fig. 2 an enlarged detail in section taken on the line 2—2 of Fig. 1; and Fig. 3 a similar view taken on the line 3—3 of Fig. 1.

Describing by reference characters the various parts shown in the drawings, 1 denotes part of the crankcase of a radial aircraft engine, such as shown in my aforesaid application, the crankcase being provided on its exterior with a plurality of flanged bases, such as shown at 2, to which the outer cylinder casings and the cylinder heads are secured by long through bolts 3, in a manner to be described in connection with the cooperating features of the respective cylinder casings whereby these bolts serve to anchor the cylinder casings and heads securely and accurately to the crankcase in a manner to avoid distortion as well as any material loss of heat dissipation from the cylinder casings.

Each cylinder comprises an outer casing 4 provided with an inlet manifold 5 extending entirely therearound and also with an exhaust manifold 6, also extending entirely therearound and located above the inlet manifold. These manifolds are provided respectively with inlet and exhaust pipes, the inlet pipe being shown at 5a. The inlet manifold communicates with a circumferential series of elongated ports 7 and the outlet manifold with similarly constructed and arranged ports 8. The supply of gaseous mixture to the ports 7 and the exhaust of the gases of combustion through the ports 8 are controlled by the novel valve construction forming the subject matter of the claims of

my aforesaid application Serial No. 303,942. This valve construction comprises generally a long sleeve 9 which constitutes a valve as well as the inner wall of a cylinder and which is guided throughout the major length of its movements by the inner wall 10 of an external cylinder casing. The sleeve 9 is provided, adjacent to its upper end, with a series of circumferentially arranged ports, not shown herein but shown in my application Serial No. 303,942, and which are adapted to be brought into and out of registration with the ports 8 through the reciprocatory movements of the said valve; also with a series of circumferentially arranged ports 9a which are located below the former ports and which are adapted to be brought into registration alternately with the ports 7 and 8 by such reciprocation.

Cooperating with the sleeve 9 is a selector ring 11 which is mounted for reciprocation in a cylindrical guide 12 which is provided therefor in the interior wall of the cylinder casing. This ring is provided with a series of circumferentially arranged ports 11a adapted to be brought into registration with the upper and lower ports of the sleeve valve 9 and alternately into registration with the inlet and exhaust ports 7 and 8 in the cylinder casing. The manner in which the sliding sleeve valve and the cooperating selector ring are operated is shown, described and claimed in my aforesaid application Serial No. 303,942.

Two of the cylinder heads referred to hereinbefore are shown at 13, and each cylinder casing, including the inlet and exhaust manifolds, is provided with circumferentially extending heat-dissipating fins 14.

It will be noted that, in order to secure a maximum area for the inlet and exhaust ports 7 and 8, the same extend substantially uninterruptedly about the portions of the casing provided respectively therefor, the adjacent ports of each series being separated by narrow segments 4a of the outer casing 4 and the segments that are interposed between the ports 7 registering longitudinally of the casing with the segments that are interposed between the ports 8.

In order to obtain the most effective means for securing the cylinder casings to their respective seats, whereby all distortions of the casings and the parts therewithin will be avoided, the bolts 3 are located as closely as possible to the outside wall of each casing. This is accomplished in the following manner: I provide each casing with hollow bosses 4b formed integral therewith and extending substantially the full length thereof, to

and between the top flange 4^c and the bottom flange 4^d thereof, and including the segments 4^a. Each of these bosses is provided with a bore 4^e through which the bolts 3 extend. It will be noted that these bores intersect the external surface of the cylinder casing; in fact, substantially half of each bore is located within the exterior of its cylinder casing. By this arrangement, while the heat-dissipating surface of each casing is slightly reduced by the bores formed within these bosses, this loss is at least compensated for by the extra metal contained within the bosses, which extend the complete length of the cylinder casings. The heat-dissipating fins 14 extend around and between the bosses 4^b and are formed with said bosses and with the cylinder casing of which the bosses form a part.

In assembling, the bolts 3 are screwed home in their respective flanged seats 2 and the cylinder casings, together with their respective heads, are then dropped over the bolts, after which the nuts on the outer ends of the bolts are set up, whereby the cylinder casings and their respective heads are anchored securely in place. Short bolts 15 also secure the flanges 4^d to the flanged bases 2.

It will be noted that, due to the inter-relation between the structure of the cylinder unit (comprising the head and the outer casing) and the bolts 3, the said bolts actually form part of this cylinder unit, being of the same effective length as the length of the said unit.

Due to the means which I employ for anchoring the cylinder casings to their respective bases, I am enabled to remove stresses from the said casings and from the walls thereof as a whole and to counteract the effects of fatigue which will necessarily be set up through prolonged operation of the engine, and particularly where aluminum or aluminum alloys are employed in the cylinder construction and where large proportions of circumferential zones of the cylinder casings have been removed as a necessary incident to providing the same with circumferential series of ports, such as are shown herein. Due to the manner in which the cylinder casings and heads are anchored to the crankcase, I am enabled to obtain the advantages arising from providing the cylinder casings each with an upper and a lower series of ports extending around and occupying the greater portion of the entire circumference thereof and at the same time to protect the por-

tions of the casings thus weakened against fracture and distortion.

Due to the fact that the bores of the bosses in which the bolts or tie rods are located intersect the outer surface of the cylinder casing, the bolts or tie rods are thereby located as closely as possible to the center of the cylinder. This prevents a distortion of the head and destruction of the head gasket and enables me to accomplish these important objectives with a far smaller number of bolts or tie rods than are customarily employed.

Having thus described my invention, what I claim is:

1. The combination, with a crankcase provided with a cylinder-supporting base, a casing having an outwardly projecting bottom flange adapted to be secured to and upon said base and an outwardly projecting top flange, and a head provided with a flange adapted to overlie the top flange of the casing, the said casing being provided with a circumferential series of inlet ports extending substantially therearound and with a circumferential series of exhaust ports extending substantially therearound and spaced longitudinally of the casing from the series of inlet ports, the ports in each said series being separated by segments of said casing and the segments of the casing which are interposed between the ports of one series registering longitudinally of the casing with the segments interposed between the ports of the other series, of means for anchoring the said head and casing to the said base, the said means comprising hollow bosses formed on the outer wall of the casing, and including the aforesaid segments thereof and each of the said bosses extending uninterruptedly between and in proximity to the top and bottom flanges of the casing, and bolts extending through the bores of said bosses and the casing flanges and the cylinder head flange and into the base and connecting the casing and the cylinder head with the said base.
2. In the organization recited in claim 1, the casing being of the type provided with heat radiating fins, the said bosses, intersecting the fins adjacent the latter's junction with the outer surface of the casing and the axes of the bores of the said bosses being substantially coincident with the outer surface of the casing.

CLIFFORD S. GOBY.
